MACHINE FOR FINISHING THE HEADS OF BOLTS, SCREWS, AND THE LIKE

Louis S. Burbank, deceased, late of Worcester, Mass.; by Davis E. Burbank, administrator, Worcester, Mass., assignor, by mesne assignments, to The Waterbury Farrel Foundry and Machine Company, Waterbury, Conn., a Corporation of Connecticut

Original application June 7, 1928, Serial No. 283,469. Divided and this application April 10, 1931. Serial No. 529,162

4 Claims. (Cl. 10—20)

The present invention relates to the manufacture of bolts, screws and the like from elongated pieces of metal, this application being a division of the original application of said Louis S. Burbank, deceased, Serial No. 283,469, filed June 7, 1928.

In the aforesaid copending application, there is shown and described a machine for producing bolts, screws, and the like, characterized by the provision of a series of cooperating punches and dies adapted to perform a series of developing operations upon an elongated metal blank, so that each stroke of the machine is adapted to cause a discharge of a completed blank therefrom. In the operating cycle of this machine, the last step in producing the completed blank resides in operations which result in trimming and otherwise finishing the head of the blank, and the present application relates to instrumentalities for obtaining this result.

Briefly stated, the invention of the present application resides in means for operating upon the unfinished head of a blank by a pair of cooperating die and punch elements which are adapted to trim the head so as to impart a symmetrical form thereto and to finish the trimmed faces of the head as by burnishing, the above results being accomplished by an extremely simple mechanism effective during one complete operative stroke of the machine. While, for purposes of illustration, the head trimming and finishing mechanism is shown associated with other parts of the machine of the original application Serial No. 283,469, obviously the mechanism of the present application can be employed separately, or in combination with other mechanisms for producing a blank with an unfinished head, all as will hereinafter appear from the following description with reference to the accompanying drawings, in which:

Fig. 1 is a plan view of a machine embodying the mechanism of the present invention.

Fig. 2 is a vertical sectional view along the line 2—2 of Fig. 1, looking in the direction of the arrows and showing the parts on an enlarged scale.

Fig. 2a is a fragmentary sectional view along the line 2a—2a of Fig. 1.

Fig. 3 is a horizontal sectional view on an enlarged scale along the line 3—3 of Fig. 2, looking in the direction of the arrows.

Fig. 4 is a fragmentary sectional view showing on an enlarged scale the position of the parts at the start of the head trimming and finishing operation.

Fig. 5 is a fragmentary view, similar to Fig. 4, illustrating the head trimming operation partially performed.

Fig. 6 is a fragmentary view, similar to Fig. 5, illustrating the head trimming operation completed.

Fig. 7 is a fragmentary view, similar to Fig. 6, illustrating the performance of the head finishing operation and the ejection of the completed blank.

Like reference characters refer to like parts throughout the drawings.

Referring first to Figs. 1 and 2, the invention is shown, for purposes of illustration, as being embodied in a machine of the type shown and described in the original copending application Serial No. 283,469, and since this particular machine is fully described therein, only such portions thereof will be described in the present application as are necessary for a complete understanding of the invention. The machine generally comprises a frame 1 which rotatably supports a shaft 2 adapted to be driven in any suitable manner, as by a belt on one of the flywheels 3. As best shown in Fig. 2, the shaft 2 provides a centrally disposed crank portion 4 connected at its free end to a head or ram 5 slidable in guideways 6 provided by the frame, so that each revolution of the shaft imparts a complete reciprocal or back-and-forth movement to the head 5.

As best shown in Fig. 1, the metal stock from which the blanks are made is preferably provided in the form of a wire 7 coiled upon a reel 8 rotatably mounted so that wire 7 may be drawn therefrom by a pair of grooved feed rolls 9. The rolls are adapted to be intermittently rotated by means of a suitable ratcheting mechanism, indicated at 10, connected to the driving shaft 2 by means of a rod 11, so that each revolution of the shaft 2 is adapted to cause the rolls 9 to grip and feed a predetermined length of wire 7 toward the head 5. As shown in dotted lines in Fig. 1, the wire 7 is projected through an opening 12 in the frame 1 until it comes into engagement with a wire stop 13. Then gripping knives 14 mounted on a reciprocating slide 15, movable at right angles to the line of wire feed, by cams 16 and 17 on a shaft 18 sever a blank of predetermined length from the wire and carry it into register with a cooperating punch A and cooperating die, as indicated in dotted lines.

As fully described in my copending original application Serial No. 283,469, rotation of the crank shaft 2 with resulting reciprocal movement of

the head 5 causes a developing operation to be performed on the blank 7a by the cooperation of the punch A and cooperating die following which the blank is ejected from the die. The ejected 5 blank is thereupon seized by oscillatory transfer fingers, indicated at 19 in Fig. 1, which fingers convey the blank into register with a second punch B and cooperating die. Each reciprocation of the head 5 is adapted to cause the punch 10 B and its die to perform a second developing operation upon the blank, after which it is ejected so that it may be seized by a second set of transfer fingers 20 and conveyed into register with a third punch C and die C'. The blank 7a then 15 appears as shown in Fig. 4 with a roughly formed generally cylindrical head portion 21, and the present invention resides in the form and operation of the cooperating punch C and die C' whereby one complete reciprocation of the head 20 5 will cause the head 21 of the blank to be trimmed, finished, and finally ejected from the machine.

As best shown in Figs. 4 and 5, the punch assembly designated by the reference character 25 C comprises a main cylindrical punch member 22 received within an opening 23 provided in the head 5 with a pressure block 24 positioned at the rear of the member 22. The punch member 22 provides a central opening 25 which receives 30 a plunger 26 polygonal in cross section, and since the front end of the punch member 22 is beveled rearwardly, as indicated at 27, the plunger 26 is surrounded by a sharp polygonal cutting edge 28. The plunger 26 extends rearwardly into an 35 enlargement 25a of the opening 25, and a head 29 of the plunger 26 is engaged by a spring 30, the pressure of which tends to yieldingly maintain the end of the plunger 26 beyond the cutting edge 28. The plunger 26 provides a central opening 31 in which is received the reduced end of 40 an ejector pin 32 passing through the spring 30. The larger end of the ejector pin 32 is adapted to be engaged by a lever 33 which, as best shown in Fig. 2, is pivoted at 34 upon the 45 punch carrying head 5 with its lower end extending below the under surface of the head 5. A spring 35 serves to maintain the intermediate portion of the lever 33 in yielding engagement with the end of the ejector pin 32, so as to maintain 50 the opposite end of the pin within the opening 31 in the plunger 26. The lower end of the lever 33 is adapted to engage a stop 36, adjustably mounted on the frame, upon completion of return movement of the head to thereby cause 55 the pin 32 to eject a completed blank from the punch C in a manner which will hereinafter appear.

Referring again to Fig. 4, the die assembly, designated by the reference character C', comprises a cylindrical die member 37 providing a central opening 37a for freely receiving a sleeve 38 having the same external form as the polygonal plunger 26. The die sleeve 38 provides a central opening 39 of such diameter as to freely receive the body portion of the blank 7c when the blank is projected toward the die C' by the advancing punch C. The front end of the die member 37 is beveled rearwardly at 40 so that the rim of the opening 37a provides a cutting 65 edge 41 of exactly the same form as the cutting edge 28 of the punch member 22. The rear end of the sleeve 38 within the die opening 37a is adapted to be engaged by a plunger 42 which, as best shown in Fig. 3, is adapted to be moved axially by means of a rockshaft 43 rotatably mount-

ed within a bushing 44 carried by the frame 1. The rockshaft 43 is cut away at diametrically opposite points to provide shoulders 45 and 46 which respectively engage the plunger 42 slidably mounted in its bushing 42a, and a second plunger 47 slidably mounted in its bushing 47a for imparting movement parallel to the movement of the plunger 42. The plunger 47 is partially surrounded by a coiled spring 48 engaging a collar 49 so as to yieldably maintain the plunger 47 in a position in which its right hand end portion projects beyond the end of a bushing 50 carried by the die block 51. The projecting end of the plunger 47 is in alignment with a longitudinally movable operating rod 52 slidably mounted in the frame 1. As best shown in Fig. 2a, the rear end of the operating rod 52 projects beyond a portion 53 of the frame 1 so that, as the punch head 5 completes its forward stroke, the projecting end of the rod 52 is adapted to be struck by means of an adjustable abutment 54 carried by the head 5. Obviously, such engagement between the abutment 54 and the operating rod 52 will drive the plunger 47 inwardly to turn the rockshaft 43, thereby imparting movement in the opposite direction to the plunger 42 and the punch sleeve 38 for a purpose which will shortly appear.

When the blank 7a, with its rough cylindrical head 21, is transferred into register with the third die C' and is engaged by the advancing end of the projecting punch plunger 26, the body of the blank enters freely into the opening 39 of the die sleeve 38 until the head 21 engages the cutting edge 41 of the die member 37, thereby checking the movement of the blank 7a. When this occurs, the plunger 26 yields inwardly so that the cutting edge 28 of the punch member 22 engages the opposite side of the head 21 almost simultaneously with the engagement of the cutting edge 41 with the head 21. Therefore, continued movement of the punch 22 causes the head 21 to be cut from opposite sides, as indicated in Fig. 5. As the cutting edges 28 and 41 nearly meet each other, at the end of the forward movement of the punch head 5, the sleeve 38 is moved quickly toward the punch member 22 by the plunger 42 through the operation of the rockshaft 43 as the rod 52 strikes the abutment 54. When this occurs, the trimmed head of the blank is forced into the opening 25 of the punch 22, the plunger 26 yielding, as indicated in Fig. 6. The result of this projection of the trimmed head into the punch member 22 is that the scarf made by the cutting edge 28 of the punch member 22 passes by the scarf started by the cutting edge 41 of the die member 37, the movement of the sleeve 38 by the plunger 42 being sufficient to entirely clear the blank head from the cutting edge 41 and enter the trimmed head completely within the punch opening 25.

At this moment, the punch carrying head 5 starts its movement away from the die C', and since the trimmed head of the blank is fully received in the punch opening 25, with frictional engagement between the polygonal faces of the head and the opening 25, the punch 22 withdraws the blank entirely from the die C', particularly as the body of the blank is freely received within the opening 39 of the sleeve 38. As the punch head reaches the end of its withdrawing movement, with the retracted plunger 26 holding the lever 33 turned back, the projecting lower end portion of the lever 33 strikes the stop 36, thereby forcing the lever 33 against the end of the pin 150

32 to cause the plunger 26 to eject the finished blank from the punch 22, as indicated in dotted lines in Fig. 7. Since this movement of the trimmed head in the punch opening 25 is in the opposite direction to the movement of the head which completed the trimming by the cutting edge 28, the surfaces of the trimmed head are burnished as the completed blank is ejected from the punch 22. At this point, it should be particularly noted that the trimming and burnishing of the head is accomplished by one complete back-and-forth movement of the punch head without pushing the blank entirely through either the punch or the die, as has been the practice heretofore. In other words, in accordance with the present invention, the trimming and burnishing of the head is carried out in what amounts to a continuous operation performed by one complete back-and-forth movement of the punch, with the burnishing being accomplished by a reversal of the direction of movement of the blank, simultaneously with its ejection from the machine.

25 What is claimed is:

1. In a machine of the class described for finishing the head of a blank having a shank, a pair of trimming tools consisting of a stationary trimming punch that receives the shank of the blank and a reciprocating trimming punch, means to reciprocate the punch and thus cut the head of the blank placed between said tools from opposite sides and to stop cutting before the opposing trimming edges meet, means made operative while the trimming is in progress to move the head of the blank completely into the trimming punch whereby the blank may be supported and carried away from the other tool and during the carry movement positively maintain its axial alignment therewith, means for withdrawing said punch with said blank frictionally held therein, to clear the blank from said die and means to finally eject said blank from the punch and into the open space between the tools.
2. In a machine of the class described for finishing the head of a blank having a shank, a pair of cutting tools consisting of a cutting die that receives the shank of the blank and a cutting punch relatively movable toward and away from each other, each tool having a continuous mating cutting edge forming a circle, polygon or other shape, the inner surface of the punch being made approximately parallel to the movement of said tool thus giving a rubbing action to the surface passed over by the cutting edge, means to reciprocate the cutting punch for the purpose of cutting the head of a blank placed between the two cutting edges when traveling in one direction, the

limit of said travel being such that the cutting edge of the cutting punch is spaced from the cutting edge of the cutting die, means made operative while the cutting is in progress to force that part of the head of the blank cut by the cutting die and between the cutting die and cutting punch completely into the cutting punch, means for moving the tool carrying the blank away from the other tool to clear the blank therefrom, and means to eject the blank from the carrying tool and into the open space between the tools.

3. In a machine of the class described for finishing the head of a blank having a shank, a pair of cutting tools consisting of a cutting die that receives the shank of the blank and a cutting punch relatively movable toward and away from each other, each of said tools having a continuous mating cutting edge forming a circle, polygon or other shape, means to reciprocate the cutting punch for the purpose of cutting the head of a blank placed between it and the cutting die when traveling in one direction, a guide in the cutting die to receive and guide the shank of the blank being cut, an ejecting plunger in the cutting punch, means for causing the end of said guide to completely project the head of the blank within the opening in the cutting punch, the said opening having approximately parallel edges which burnish the cut surface and form a friction thereon for withdrawing the blank from the guide and means near the extreme outward stroke of the cutting punch for forcing the blank out of the cutting punch by the ejecting plunger and into the open space between the tools.

4. In a machine of the class described, for finishing the head of a blank having a shank; a pair of cutting tools relatively movable toward and away from each other, with their cutting portions facing each other and one of the pair of cutting tools receiving the shank of the blank; means to cause the tools, when the blank is placed therebetween, to cut the head of the blank simultaneously from opposite sides and to stop cutting before the opposing cutting edges meet; means to move the head of the blank into that one of the cutting tools which does not receive the shank to complete the cutting operation and support the blank while being carried away from the shank receiving tool; means to move the tool with the blank supported therein away from the shank receiving tool to clear the shank therefrom; and means to eject the blank from the tool carrying the same, in a direction opposite to that from which it entered and into the open space between the tools.
